G. F. BORKMAN

ECCENTRICALLY PIVOTED ARMATURE MOUNTING FOR VIBRATORY UNITS

Filed March 31, 1926

FIG. 1.

Inventor
G. F. BORKMAN,

By Attorney

UNITED STATES PATENT OFFICE.

GEORGE F. BORKMAN, OF SALT LAKE CITY, UTAH.

ECCENTRICALLY-PIVOTED ARMATURE MOUNTING FOR VIBRATORY UNITS.

Application filed March 31, 1926. Serial No. 98,835.

This invention relates to an eccentrically pivoted armature mounting for vibratory units, and more particularly to an armature such as is used to actuate the diaphragm in sound producing and reproducing devices, such as microphones or telephone and radio receivers, and its principal objects are:

First. To overcome the reactance and lag of the armature;

Second. To substantially eliminate the ungoverned vibration of the free end of the armature, thereby reducing the natural vibration thereof, caused by the applied energy, in coming back to the normal position.

Third. To cause the armature to vibrate through a smaller angle, thereby approaching more nearly a parallel action, than is the case with the center pivoted armature.

Fourth. To cause the applied energy to exert a greater influence upon the diaphragm.

Fifth. To reduce the bending moment upon the pins where rigidly mounted pin mountings are used.

Sixth. To make possible the use of a heavier and more durable armature.

In attaining the objects just outlined, any desired method of pivoting the armature may be used, the pivot being placed to one side of the center plane of the electromagnet, but interjacent the polar extremities of the armature.

While most of the advantages obtainable through the use of this invention accrue, no matter what particular method of mounting may be employed, yet, where the well known rigid pin mounting is used, the additional advantage of reducing the bending moment upon the pivot pins, is an important consideration.

The armature may be rigidly mounted upon the pivot pins in the usual manner and the pins be rigidly fastened in the spool sleeve of the electromagnet in the customary manner. Similarly, the link connection from the diaphragm to the armature, may be of any desired type.

The features of this invention for which the protection of Letters Patent is desired, are collectively grouped in the claims concluding this specification.

In the drawing which illustrates merely one embodiment of this invention,

Fig. 1 represents a vertical center section through a radio receiver, the electromagnet thereof being shown in cross-section.

Fig. 2, a top plan, partly in section on line 2—2 in Fig. 1; and

Fig. 3, a diagram drawn to an enlarged scale, and indicating the relative movement of the armature arranged in accordance with the present invention, compared to the movement of an ordinary centrally pivoted armature.

Referring to the drawing, 10 indicates the usual permanent magnet within which may be mounted the electromagnet, whose coil 12, is held by the usual pole pieces 14 and 15. Within the sleeve 16 of the spool on which coil 12 is wound, are the rigidly secured pivot pins 17, which in turn are also rigidly secured to the armature 18.

The broken line 19 indicates the longitudinal vertical center plane of the electromagnet. It will be noted that the pivot pins 17 are located to one side of the plane 19, and upon the far side from the pin connection 20, which latter extends from the armature 18 to the diaphragm 24, this location giving rise to the term "eccentrically pivoted". Attention is directed to the fact that in all other sound producing or reproducing devices with which I am familiar, the pivot pins would be located in the center plane 19.

In the present instance is shown the auxiliary pin 21 which extends from the outer end of the short arm of the armature to the pin connection 20, but this forms no part of the present invention, as the same is the subject of my appending application for U. S. patent, filed April 11, 1925, Serial No. 22,474. It is shown here to make known its adaptability to, and use with, the present invention.

When the armature 18 is actuated by the energized electromagnet coil, it oscillates through an angle, indicated for convenience, as *abc* in the diagram, (Fig. 3). In this figure *mm* indicates the center or neutral position of the armature. It is convenient to use the same figure to compare the results of mounting the armature in the ordinary centrally pivoted manner, with the results of mounting it in the eccentric manner of the present invention. Where the armature is fastened to the pins 17, in Fig. 1, is indicated by *b* in Fig. 3, and the fastening of the pivot pin in the spool sleeve 16, is indicated in Fig. 3 at *l*.

Now, for comparison: in the usual center

pivoting of the armature mn , the angle afc indicates the limit of oscillation thereof, ar and eg representing the extreme positions of the armature. The line fk represents the pivot pin of the centrally pivoted diaphragm in its neutral position, the line gh the nominal position thereof when the armature is in the position ar .

Similarly, the line bl represents the eccentric pivoting of the same armature mn , this forming the salient feature of the present invention.

The lines el and dl represent the nominal positions of the pivot pins when the eccentrically pivoted armature is in the extreme positions ap and co respectively.

It is obvious that the angle abc is considerably less than the angle afc , and also that the angles eld and ghh are respectively equal to the angles abc and afc .

Comparing the actions of the two methods of mounting the armature mn , we will consider first its center pivoting at f . Supposing the end m of the armature to be in its central position, the electromagnetic action upon both extremities of the armature will cause the armature to be jerked about the center of oscillation h and the free end m to flop through angular space in an ungoverned way, this resulting in a reactance and lag upon the sound vibrations of the diaphragm.

The action of the armature mn when mounted on the eccentric pivot pin bl as in the present invention, the end m again being supposed to be pivoted to the diaphragm, would be to oscillate around the center l leaving only the short arm bn ungoverned, thus reducing the objectionable reactance and lag very materially. Where the auxiliary pin 21 is connected to the short arm, this small reactance and lag would be reduced to almost zero.

It is obvious that the flexing of the pivot pin bl acting through the angle eld would be much less than the flexing of the pivot pin fk acting through the angle gha , thereby lengthening the life of the pivot pin and its fastenings materially.

Owing to the length of the lever arm mb compared with the length mf , the armature in the eccentrically pivoted form may be made of heavier material than in the centrally pivoted form.

While a typical embodiment of this in-

vention is herein shown and described, it should be clearly understood that all the detailed parts thereof, may or may not, appear in the preferred forms, and also, that the preferred forms may be varied from time to time, depending upon the circumstances and conditions governing and governed by, the development of this invention and the arts to which it is incident, therefore the scope of this invention may be ascertained from the claims in which its spirit is generalized.

Having fully described my invention, what I claim is:

1. A vibratory unit comprising a spool 70 having a sleeve with its winding, armature mounting pins eccentrically located within the said sleeve, and an armature operatively mounted upon said pins.

2. A vibratory unit comprising a sleeve 75 and a coil wound upon said sleeve, rigidly disposed pivot pins eccentrically located within said sleeve and an armature rigidly fastened to the said pivot pins.

3. In an eccentrically pivoted armature 80 mounting, an electromagnet spool having a sleeve, pins projecting inwardly from said sleeve, said pins being spaced apart from each other along a line lying between the open ends of said sleeve, said line being 85 spaced apart from the center line lying between said open ends, and an armature mounted on said pins.

4. An armature and mounting, comprising a supporting structure, pivots secured in 90 said structure, and an armature mounted on said pivots, the points at which said armature is connected to said pivots lying in a straight line located between the polar extremities of the armature, said line being 95 spaced apart from the line lying midway between the said armature extremities.

5. In an eccentrically pivoted armature mounting, an armature, pole pieces having polar extremities in proximity to both ends 100 of said armature, and a pivotal mounting for said armature, the pivotal axis lying interjacent the ends of the armature and interjacent the said polar extremities, but to one side of the longitudinal vertical center 105 plane between said polar extremities.

In testimony whereof, I sign my name hereto.

GEORGE F. BORKMAN.
